UNITED STATES PATENT OFFICE.

CHARLES N. WARNER, OF NEW YORK, N. Y.

DIAPHRAGM-MOUNTING.

1,372,054.

Specification of Letters Patent. Patented Mar. 22, 1921.

Application filed April 28, 1920. Serial No. 377,162.

To all whom it may concern:

Be it known that I, CHARLES N. WARNER, a citizen of the United States, residing at the city of New York, in the county of New York and State of New York, have invented certain new and useful Improvements in Diaphragm-Mountings, of which the following is a full, clear, and exact description.

10 This invention relates to diaphragm mountings for acoustical instruments and similar devices, and has especial value when used in talking machine sound boxes.

One object of my invention is to provide 15 a mounting which will support the diaphragm in a proper operative position and yet permit of a response by the diaphragm to sound waves or the oscillations of a stylus, which will be as free as possible 20 from the restraints of mechanical parts and thus obtain a more perfect reproduction or recordation.

A further object is to provide a diaphragm mounting which is readily adaptable 25 for use in sound boxes for talking machines and the like, and which is durable in use and inexpensive.

A further object is to provide a diaphragm mounting which will generally improve 30 the quality of the sound emitted by the instrument containing the same.

Other objects and advantages will be apparent from the following description and the novel features of my invention will be 35 particularly pointed out in claims.

In one of its aspects my invention comprehends a peripheral groove or recess containing a heavy viscous substance such as a heavy oil or petroleum jelly over which the 40 diaphragm is placed with a face in contact with the viscous substance.

It also comprehends the support of the diaphragm on one side by means of small 45 diametrically opposed abutments for slightly limiting vibratory movement in one direction.

In the drawings:

Figure 1 is a sectional elevation of one embodiment of my invention; 50 Fig. 2 is a front elevation of the casing and diaphragm, the latter being partly broken away to show certain details;

Fig. 3 is a partial sectional elevation of a slightly modified construction;

Fig. 4 is a partial sectional elevation of another modification, and

Fig. 5 is a partial sectional elevation of still another modification.

In the illustrated embodiments, the casing 1 is provided with a diaphragm chamber or depression 2, formed by the peripheral flange 3. Secured to the edge of the flange 3 by suitable means such as screws 4 is an annular ring 5 having a flange 6 extending from its inner periphery into the chamber 60 2 to form with the flange 3 an annular or peripheral groove 7. The groove is filled with a suitable viscous substance 8 such as heavy oils or petroleum jelly, and the diaphragm 9 is positioned in the chamber 2 65 with one face thereof covering the groove and in contact with the viscous substance 8. For slightly limiting the vibratory movement of the diaphragm I may provide on the casing in the depression 2 a pair of small 70 abutments 10, disposed between the diaphragm 9 and casing 1 and on the side of the diaphragm opposite from the flange 6. The abutments 10 are also arranged along substantially diametrically opposed edges of 80 the diaphragm. The diaphragm may be of any suitable material such as those commonly in use, but if it is of wood, the abutments 10 are preferably arranged at the ends of a diameter of the diaphragm which 85 extends transversely of the grain of the wood, since the flexure of the diaphragm is, in such a case, along the grain of the wood which I have found provides a more sensitive instrument. The abutments may be 90 omitted if desired, although I have found their use to be desirable.

In order to prevent egress of the viscous substance during long continued use I may line the groove with one or more of the 95 flexible strips 11 and 12 which project from the groove toward and into engagement with the diaphragm to thus more effectively confine the viscous substance.

I may also form the annular ring 5 and 100 its flange 6 of a slightly flexible yielding material such as rubber, or construct it of the shape indicated in Fig. 4. I may also provide the groove and viscous substance on both sides of the diaphragm, if desired, as 105 illustrated in Fig. 5.

While I have mentioned petroleum jelly or heavy oils as suitable fillers for the

grooves I do not desire to be limited thereto as various other jellies or viscous substances may be used equally well. The other parts may be of any suitable material and for the 5 lining strips I have found waxed or glazed paper to be very satisfactory. With a talking machine sound box provided with a diaphragm mounted in accordance with my invention, I find the tones and sound waves 10 produced thereby to be clearer, more distinct and round, and generally more natural and pleasing. I find that with such a box, very low or faint sounds such as those of the piano or harp which heretofore have 15 been difficult of satisfactory reproduction, are reproduced in a clear, loud, and natural manner, while the box is equally satisfactory, when used with records having notes of a very high pitch. I have also found 20 that the heavier the oil or viscous substance the more prominently will the bass be brought out. Heretofore difficulty has been experienced by so-called "blasting" of the diaphragm when notes of high frequency 25 are being reproduced, but with a box having my invention embodied therein "blasting" is prevented or avoided.

It is obvious that various changes in the 30 embodiments herein described and illustrated may be made within the principle and scope of my invention.

I claim:

1. A diaphragm mounting comprising a support provided with a peripherally arranged 35 groove, a viscous substance filling said groove, and a diaphragm having one face covering said groove and in contact with the viscous substance.

2. A diaphragm mounting comprising a support provided with a peripherally extending 40 groove, a viscous substance filling said groove, a diaphragm having one face covering said groove and in contact with the viscous substance, and a pair of short abutments 45 along the peripheral portion on opposite sides of the center of the diaphragm and on the side opposite from the groove for slightly limiting the movement of the diaphragm away from the groove.

3. A diaphragm mounting comprising a support provided with a peripherally extending 50 groove, a viscous substance filling said groove, a diaphragm having one face covering said groove and in contact with the viscous substance, and a flexible lining member in said groove extending outwardly into contact with the diaphragm.

4. A diaphragm mounting comprising a support provided with a peripherally extending 60 groove, a viscous substance filling said groove, a diaphragm having one face covering said groove and in contact with the viscous substance, a pair of short abutments 65 along the peripheral portion on opposite sides of the center of the diaphragm and on

the side opposite from the groove for slightly limiting the movement of the diaphragm away from the groove, and a flexible lining member in said groove extending outwardly into contact with the diaphragm. 70

5. A diaphragm mounting comprising a support provided with a resilient portion extending from and forming with the remainder of the support a peripherally extending groove, a viscous substance filling 75 said groove, and a diaphragm having one face covering the groove and in contact with the viscous substance.

6. A diaphragm mounting comprising a support provided with a resilient portion 80 extending from and forming with the remainder of the support a peripherally extending groove, a viscous substance filling said groove, a diaphragm having one face covering the groove and in contact with the 85 viscous substance, and a flexible lining in said groove extending outwardly into engagement with the diaphragm.

7. A diaphragm mounting comprising a frame, a rubber extension on said frame 90 forming therewith a peripherally extending groove, a viscous substance filling said groove, and a diaphragm within the frame and having one face covering the groove and in contact with the viscous substance. 95

8. A diaphragm mounting comprising a frame, a rubber extension on said frame forming therewith a peripherally extending groove, a viscous substance filling said groove, a diaphragm within the frame and 100 having one face covering the groove and in contact with the viscous substance, and a flexible lining in said groove extending outwardly into engagement with the diaphragm. 105

9. A diaphragm mounting comprising a frame, a rubber extension on said frame forming therewith a peripherally extending groove, a viscous substance filling said groove, a diaphragm within the frame and 110 having one face covering the groove and in contact with the viscous substance, and means abutting the side of the diaphragm opposite from the groove for slightly limiting 115 movement of the diaphragm away from the groove. 115

10. A diaphragm mounting comprising a support, a wooden diaphragm, means carried by said support for yieldingly limiting vibratory movement in one direction, and a pair of short abutments carried by the support for slightly limiting vibratory movement of the diaphragm in the other direction, said abutments being disposed substantially at opposite ends of a diameter of the 120 diaphragm which is transverse to the grain of the wood. 125

In witness whereof I hereunto subscribe my signature.

CHARLES N. WARNER.
